UNITED STATES PATENT OFFICE.

RALPH E. WILLIAMS, OF SANTA ANA, CALIFORNIA.

ELECTRIC LAMP.

1,299,888.

Specification of Letters Patent.

Patented Apr. 8, 1919.

Application filed May 20, 1918. Serial No. 235,481.

To all whom it may concern:

Be it known that I, RALPH E. WILLIAMS, a citizen of the United States, residing at Santa Ana, in the county of Orange, State 5 of California, have invented new and useful Improvements in Electric Lamps, of which the following is a specification.

This invention relates to search lights and more particularly to what is generally known as a spotlight adapted particularly for automobiles, although useful for other purposes; and it is a general object of this invention to provide an improved form of spotlight. The improvements herein concerned have to do mainly with improved construction of the spotlight for the purpose of excluding moisture from the interior of the light structure and for the purposes of facilitating and reducing expense of manufacture and assembly.

In many spotlights now upon the market, moisture readily finds access to the interior of light structure, passing into the interior of the reflector around the lamp and there 25 forming a vapor which decreases the effectiveness of the light and tarnishes the reflector. It is an object of this invention to provide a construction whereby moisture is entirely excluded. This object, and other 30 objects, are accomplished by the construction and organization hereinafter explained in detail. In the following detailed specification I explain and describe different forms of lamp which embody the moisture excluding feature; and I further explain a preferred specific construction which has other advantages in cheapness of manufacture and ease of assembly, together with simple and easy operation. For the purpose of this 40 specification I refer to the accompanying drawings in which—

Figure 1 is a vertical longitudinal section showing a preferred form of my lamp; Fig. 2 is an enlarged detail section of parts shown in Fig. 1; Fig. 3 is a cross section on line 3—3 of Fig. 6; Fig. 4 is a cross section on line 4—4 of Fig. 6; Fig. 5 is a cross section on line 5—5 of Fig. 6; Fig. 6 is an enlargement of a part of Fig. 5; and Fig. 7 is a view 50 similar to Fig. 1 showing a modified form of construction.

In the drawings the numeral 10 designates the reflector within which the electric lamp 11 is mounted. A lens glass 12 is secured by 55 any suitable means over the front of the reflector. I preferably use an annular clamp-

ing ring 13 and interpose a gasket of some suitable material at 14 between the glass and the front edge of the reflector; the clamping ring clamping the glass tightly so that moisture cannot enter the reflector at this point. At 15 I show a sleeve upon which the reflector is mounted, and this sleeve is carried upon a bracket or standard 16. Usually the standard 16 is mounted upon or forms a part 60 of a universal joint which enables the lamp to be thrown to any desired position; but this universal joint does not form any part of the present invention.

Sleeve 15 carries within it the longitudinally slidable tube 17 which may be held in any adjusted position by a set screw 18, or by any other suitable holding means. At its forward end this tube 17 receives the base 19 of lamp 11, the lamp base having pins 20 70 which enter slots 21 in the end of tube 17, the slots being of such shape as to hold the plug in the end of the tube and hold the base contacts against the spring supported contact pins 22 which are mounted in the plug 75 23 of insulating material within the tube 17. At the back end of plug 23 there is another pair of spring supported contact pins 23 and 24. Pin 24 is longer than pin 23 and remains in engagement with contacts 25 of 80 plug 26 whether that switch plug is in the position shown in Fig. 1 or in the position shown in Fig. 2. The switch plug 26 is mounted in a cap or shell 27 which preferably fits over the end of tube 17 and also, as will 85 90 be hereinafter explained, fits over the ends of sleeve 15. Plug 26 is carried in this cap 27 and may be moved longitudinally, between the positions shown in Figs. 1 and 2, by longitudinal movement of the cap. The 95 cap 27 carries two sets of pins 30 and 31 which project inwardly and project into slots 32 cut in the opposite walls of the outer end of tube 17. These slots 32 are of a peculiar configuration which causes the pins 100 30 and 31 to be engaged and hold the plug 26 in either the position shown in Fig. 1 or the position shown in Fig. 2, the plug being moved from one position to the other either by a simple longitudinal movement or by 105 longitudinal movement accompanied by a slight twist. For instance, when the plug is moved from the position shown in Fig. 2 to the position shown in Fig. 1, it is merely pushed straight inwardly and the pin 31 will 110 then pass into the part 32a of slot 32, causing the pins 30 and 31 to move downwardly

while they move to the left (in Fig. 6) and causing the pin 30 to strike the edge of the slot at about the point designated 32^b when the pin 31 has passed to the left of the overhanging hook point 32^c. Engagement of pin 30 at the point 32^b will then cause the upward movement of the pins 30 and 31 (in Fig. 6) causing pin 31 to move in behind the hook 32^c and then lie in the position in which pin 30 is shown in Fig. 6. This carries the pins (both sets of pins 30 and 31) to the position shown in Fig. 1. The plug 26 is thus held in its inner position; and in this position both the contacts engage with the contact pins 23 and 24, closing the circuit through the device to the lamp 11. Now when it is desired to move the plug out, it is only necessary to press it slightly inwardly and then rotate it in such a direction as to carry the pin 31 (the one shown in Fig. 2) down below the hook 32^c, and then to allow the plug to be moved outwardly. This outward movement is accomplished by the spring 35 behind the long pin 24.

I have explained the action of this kind of switch tube, its contacts and plug, etc., merely for the purpose of explaining clearly and fully just what my invention is. I do not claim any invention in this particular kind of switch tube, contacts, plugs, etc., nor in the particular shape or action of the slots 32.

In the specific form of construction now described, certain features of my invention reside in the means of holding the plug 26 in place in the shell 27. The rear end of the plug bears back against a shoulder 40 at a reduced rear portion of the cap where the connecting wires 41 pass out; and the spring 35 and contact pin 24 serve the purpose of always holding the plug back against the rear of the shell 27. Now, heretofore it has been the practice to put the pins 30 and 31 upon the plugs and allow those pins to project outwardly into the slots 32. I prefer to put the pins 30 and 31 in the shell rather than in the plug for several reasons and primarily for the reason that this placement of the pin facilitates and simplifies construction and assembly. The function of the pins 30 and 31 is ultimately merely to hold the shell on the tube 15 in two different positions. With the shell thus held against movement of the tube, and with the plug 26 pressed back into the end of the shell by the action of spring 35, it then only becomes necessary to connect the shell and plug together in some manner so as to put them in a fixed position as regards relative rotation; so as to keep the contacts 25 in a certain fixed position with reference to the pins 30 and 31, so as to insure contact 25 always engaging the contact pins 23 and 24. Now this rotational connection between the plug and shell may be very easily effected. For

instance, I place a pin 45 in the shell, projecting inwardly. The back end of plug 26 preferably has an enlarged portion or flange 46 which fits the interior of the shell 27; and in this enlarged portion or flange 46 I form a notch 47. In fact, two such notches as 47 are formed oppositely; and the pin 45 is preferably placed directly behind one of the pins 31. In assembling, the plug 26 is then merely passed into the shell 27, the notches 47 passing the pins 30 and 31 and then one of the notches 47 coming into register with the pin 45. The plug fits the shell more or less loosely, so that it is easily dropped into place, or pulled into place, by use of the wire 41; and it is not necessary that the pin 45 and notch 47 fit tightly.

The form of lamp shown in Fig. 6 is in many respects similar to the form shown in the other figures; but in the lamp of Fig. 6 I use a different form of switch tube device. In this form the switch plug 26^a carries its own pin or pins 30^a engaging in the slot or slots 32^a in tube 17. The plug 26^a may be mounted in its cap 27^a in any suitable manner, as by being screwed into the cap. In this form of device it is rotation of the plug that causes making and breaking of the circuit to lamp 11. This form of switch tube, contacts, plug, etc., is very well known and needs no particular description.

Now, in each one of these forms of devices the sleeve 15 extends rearwardly close to or over the end of the switch tube 17; and the cap 27 or 27^a fits over the end of the sleeve 15. In the form shown in Fig. 1 the cap preferably fits over the end of tube 17 also; the cap being preferably (but not necessarily) in the form of a two diameter shell fitting over the sleeve 15 in its forward part and over the tube 17 in its rearward part. In the form shown in Fig. 6 the cap does not fit over or upon tube 17 but upon the sleeve 15 only. Now, heretofore, lamps of this general character have been made in which the cap has fitted over the rear end of tube 17, but sleeve 15 has been stopped short of the end of the tube; or in another construction the cap (forming a handle) has been fitted within the sleeve 15, which for that purpose extends beyond the rear end of tube 17. Now in the practical use of spot lights they usually stand (and are required by law in many States so to stand) in a slightly downwardly inclined position; and the result has been that moisture (rain, fog, etc.) which has dropped upon the cap or handle has then passed down and forwardly around the tube 17 and found access to the interior of the reflector. My present construction obviates this difficulty entirely. Any moisture which falls upon either of the caps will be shed without any possibility of its entering the sleeve 15 and passing around the tube 17 into the interior of the reflector.

Furthermore, I have an improved arrangement and construction of the reflector mounting which makes a totally moisture proof and simple joint between the reflector and sleeve 15. Heretofore, a base member such as is illustrated at 50 has been soldered or brazed to the back side of the reflector 10 and then this base member has been screw threaded onto sleeve 15. I now mount the reflector upon the sleeve by spreading or expanding the inner periphery 51 of the reflector into an annular groove 52 on the inside of the forward end of sleeve 15. The reflector base 50, in the form of a flange, is merely slipped onto the forward end of sleeve 15, bearing back against a shoulder 53, the reflector is put in place, and the inner periphery 51 expanded into groove 52, making a water proof joint at that point. The reflector is by this procedure drawn back tightly against the flange 50 and a more or less water proof joint is made between the reflector and the flange 50. Furthermore, in expanding the part 51, the forward thin part 54 of sleeve 15 is usually expanded to make a tight joint between the part 54 and member 50. The reflector is thus mounted in a simple manner upon sleeve 15, rigidly and permanently; and all this is done with a simple operation and without the necessity of soldering or brazing the flange 50 to the reflector.

Having described a preferred form of my invention, I claim:

1. In combination, an imperforate sleeve, a reflector mounted on one end of the sleeve with a water-proof joint between the reflector and sleeve, switch means contained within the sleeve, and means for operating the switch means embodying a cap fitting completely over the end of the sleeve.

2. In combination, a sleeve, a reflector mounted on one end of the sleeve with a water-proof joint between the reflector and sleeve, a lamp-holding- and switch-tube in the sleeve, switch means embodying a plug projecting into the switch tube, the sleeve extending substantially to the end of the switch tube, and a cap for the plug, said cap extending and fitting over the end of the sleeve.

3. In combination, a sleeve, a reflector mounted on one end of the sleeve with a water-proof joint between the reflector and sleeve, a lamp-holding- and switch-tube in the sleeve, switch means embodying a plug projecting into the switch tube, the sleeve extending substantially to the end of the switch tube, and a cap for the plug, said cap extending and fitting over the ends of the switch tube and of the sleeve.

4. In a device of the character described, a tube, a switch device therein embodying a plug and a spring means tending to press the plug away from the tube, a cap in which

the plug is loosely mounted, and the cap having means engaging the tube to hold the plug toward the tube against the action of said spring means.

5. In a device of the character described, a tube, a switch device therein embodying a plug fitting into the end of the tube and longitudinally movable therein, and a spring means tending to press the plug out of the tube, a cap in which the plug is loosely mounted, said cap extending over the plug and extending over the end of the tube, means on the cap and tube adapted to interengage and prevent movement of the cap, and means for preventing relative rotation between the plug and cap.

6. In a device of the character described, a tube, a switch device therein embodying a plug fitting into the end of the tube and longitudinally movable therein, and a spring means tending to press the plug out of the tube, a cap in which the plug is loosely mounted, said cap extending over the plug and extending over the end of the tube, means on the cap and tube adapted to interengage and prevent outward movement of the cap, and means for preventing relative rotation between the plug and cap, said means embodying a pin projecting into the cap and a notch in the plug adapted to fit around the pin.

7. In a device of the character described, a tube, a switch device therein embodying a plug fitting into the end of the tube and longitudinally movable therein, and a spring means tending to press the plug out of the tube, a cap in which the plug is loosely mounted, said cap extending over the plug and extending over the end of the tube, means on the cap and tube adapted to interengage and prevent outward movement of the cap, said means embodying a slot in the end of the tube and a pin projecting into the cap and engaging in said slot, and means for preventing relative rotation between the cap and the plug, said means embodying a pin projecting inwardly into the cap and the plug having a peripheral notch adapted to pass by the first mentioned pin when the plug is inserted in the cap and adapted to fit over the second mentioned pin when the plug is in position in the cap.

8. In a device of the character described, a sleeve, a switch tube in said sleeve, with its end projecting somewhat beyond the end of the sleeve, switch means in said tube embodying spring pressed contacts movable longitudinally of the tube and embodying a co-operating contact plug movable longitudinally in the end of the tube, one of said spring pressed contacts tending to press the plug out of the tube, a cap in which the plug is loosely mounted, said cap extending and fitting over the end of the sleeve, and inter-engaging means on the cap

and tube to prevent outward movement of the plug and cap.

9. In combination, a sleeve, a reflector mounted on one end of the sleeve with a waterproof joint between the reflector and sleeve, a lamp-holding- and switch-tube in the sleeve adapted to hold a lamp in its end in the reflector and having its other end projecting somewhat beyond the end of the sleeve, switch means in said tube embodying spring pressed contacts movable longitudinally of the tube and embodying a coöperating contact plug movable longitudinally in the end of the tube, one of said spring pressed contacts tending to press the plug

out of the tube, a cap in which the plug is loosely mounted, said cap extending over the end of the tube and extending and fitting over the end of the sleeve, inter-engaging means on the cap and tube to prevent outward movement of the plug and cap, the cap making a substantially tight movement fit upon the end of the sleeve.

In witness that I claim the foregoing I have hereunto subscribed my name this 29th day of April, 1918.

RALPH E. WILLIAMS

Witness:

VIRGINIA I. BERINGER.
